UNITED STATES PATENT OFFICE

169,571

COMBINED WHISK BROOM AND WINDOW WIPER

Nicholas Abrams, Los Angeles, Calif., assignor to
Lee Products, Inc., Pasadena, Calif., a corporation of California

Application December 16, 1952, Serial No. 22,734

Term of patent 14 years

(Cl. D9—2)

To all whom it may concern:

Be it known that I, Nicholas Abrams, a citizen of the United States of America, residing at Los Angeles, in the county of Los Angeles and State of California, have invented a new, original, and ornamental Design for a Combined Whisk Broom and Window Wiper, of which the following is a specification, reference being had to the accompanying drawing, forming part thereof.

Figure 1 is a front view of the combined whisk broom and window wiper, showing my new design; Figure 2 is a rear view of the combined whisk broom and window wiper; Figure 3 is a side view of the combined whisk broom and window wiper; and Figure 4 is a top plan view of same.

I claim:

The ornamental design for a combined whisk broom and window wiper, as shown.

NICHOLAS ABRAMS.
